(Cl. D74—1)

To all whom it may concern:

Be it known that I, Robert E. Gordenier, a citizen of the United States, residing in St. Paul, county of Ramsey, and State of Minnesota, have invented a new, original, and ornamental Design for a Memorandum Sheet Holder or the like, of which the following is a specification, reference being had to the accompanying drawings, forming part thereof.

I claim:

The ornamental design for a memorandum sheet holder or the like, as shown.

ROBERT E. GORDENIER.
